UNITED STATES PATENT OFFICE.

FREDERICK N. BOURNE, OF PROVIDENCE, RHODE ISLAND.

SUIT-CASE.

No. 892,125.

Specification of Letters Patent.

Patented June 30, 1908.

Application filed May 3, 1907. Serial No. 371,746.

To all whom it may concern:

Be it known that I, FREDERICK N. BOURNE, a citizen of the United States, residing at the city of Providence, in the county of Providence and State of Rhode Island, have invented certain new and useful Improvements in Suit-Cases, of which the following is a specification, reference being had therein to the accompanying drawing.

10 This invention relates to an extendible case and has for its object to provide a suit case which may be regulated in size to accommodate itself to the quantity of clothing or other articles carried therein. It is found in 15 the practical use of cases of this character very convenient to be able to extend the same and increase its capacity so that a large amount of clothing can be carried, then again, often times a small amount of clothing and 20 other articles are desired to be carried, and if not sufficient to fill the case they will shake about and become displaced or wrinkled, but by the use of a case of my improved construction the capacity of the same may be regulated 25 to accommodate itself to the contents so that its walls will always embrace and retain the articles, holding them firmly in position. In order to accomplish this result I have provided a plurality of toggle joints, all 30 of which are designed to operate in unison to either draw together or spread apart both walls of the case at once.

With these objects in view, the invention consists of certain novel features of construction, as will be more fully described and particularly pointed out in the appended claims.

In the accompanying drawings: Figure 1—40 is a perspective view of my improved suit case contracted. Fig. 2—illustrates said case with both sides expanded. Fig. 3—is an enlarged sectional view on line 3—3 of Fig. 1, showing a pair of toggle joints mounted on its operating shaft, said shaft being supported in a center or main frame portion, the 45 outer ends of the toggle members being connected to the two extendible sides. Fig. 4—is a plan view of the mechanism with the case removed showing the relative position of the toggle joints and the shafts and gearing for 50 operating the same.

Referring to the drawings at 1 is the center or main frame of the case, which is strongly constructed and on which all of the actuating mechanism is supported. At 2 and 3 are side 55 frames adapted to slide into said main frame, one on either side thereof. The side frame

2 is provided with a hinged cover 4 which may be secured at 5 with a lock of any suitable construction, the opposite side frame 3 having a permanent cover 6.

At 7 and 8 are two parallel shafts one on either side of the main frame 1, both of said shafts being threaded at each end with right and left hand threads for the reception of the nuts 9—9 and 10—10, the shafts being rotatably held in bearings 11—11 and 12 which are permanently fixed to the sides of the main frame. The end of shaft 8 is squared and extends forward at 13 out through the side of the casing at 15 for the reception of the handle 16 by which the mechanism is actuated. At 17 is a cross shaft held to revolve in bearings 24, which are fixed to one end of this main frame, said shaft being provided with pinions 18—18 which mesh with pinions 19—19 on the ends of said shafts 7 and 8, whereby both of the side shafts are connected and caused to rotate in unison. Pivoted to the nuts 10 and 9 are the connections 20 and 21, the opposite end of connections 20 being pivoted at 22 at both ends of the side frame 2, while the connections 21 on the opposite side are pivoted at 23—23 to both ends of the opposite side frame 3.

In the operation of my improved suit case, 85 when it is desired to extend or enlarge the same it is only necessary to apply the key 16 to the squared portion 13, and turn it in one direction whereby the two opposite lines of shafting rotate in unison on each side of the center main frame, thereby gradually drawing together the members of each pair of threaded nuts and simultaneously extend both sides of the case by moving outward both of the side frames 2 and 3. By controlling the movement of these sides from four distinct points prevents the same from cramping and insures perfect working of the device. To contract the case the handle is simply turned in the opposite direction. 100

My extendible suit case is of simple and practical construction and is very convenient to carry, and when covered with leather or cloth presents a handsome and finished appearance.

Having thus described my invention, what I claim as new and desire to secure by Letters Patent, is:

1. A case comprising a central main frame, two extendible sides on said frame, and means mounted on said frame whereby said sides may be moved toward and from each 110

other on said frame any desired amount and firmly retained in that position.

2. A case comprising a central main frame, two side frames adapted to slide in said main frame, and means on said main frame whereby said side frames may be moved toward and from each other and fixed in any desired position on said main frame.

3. A case comprising a main frame, two sides adapted to slide in said main frame, a shaft on each side of said main frame, and means connecting said shafts and said sides whereby said shafts may be operated to move both of said sides in unison towards and from each other.

4. A case comprising a main frame, two sides having frames adapted to slide in said main frame, a shaft on each side of said main frame, a plurality of nuts threaded on each of said shafts, a connection from each nut to each side frame, and means whereby said nuts may be moved in unison to move said side frame towards and from each other.

5. A case comprising a main frame, two sides adapted to telescope with said frame, a shaft on each side of said frame, two pairs of nuts threaded on each of said shafts, a connection between the nuts and the sides of the case and means whereby the movement of said shafts move each pair towards and from each other to extend or contract the case.

6. A casing comprising a main frame, two

telescoping sides to said frame, and means mounted on a rotatable shaft and connected to said side frame at four distinct points whereby the same may slide in and out of said main frame without the possibility of cramping.

7. A case comprising a main frame, two side frames telescoping with said main frame, a shaft on each side of said main frame, a plurality of nuts threaded on each of said shafts, a connection from each nut to each side frame and a cross-shaft geared to each of said side shafts whereby the movement of one shaft moves all of said connections in unison to move said side frames towards or from each other.

8. A case comprising a main frame, two sides adapted to telescope with said frame, a shaft on each side of said frame, two pairs of nuts threaded on each of said shafts, a connection from each nut to each side frame, a cross shaft geared to said side shafts whereby the movement of one shaft will cause each pair of said nuts to move in unison towards and from each other and slide said sides either into or out of said main frame.

In testimony whereof I affix my signature in presence of two witnesses.
